HOSIERY PACKAGE

Douglas Hahn, Ridgewood, N. J., assignor to B. Altman & Co., New York, N. Y., a corporation of New York

Application December 4, 1947, Serial No. 789,604

2 Claims. (Cl. 206—46)

1

This invention relates to an improved hosiery package having features which render it particularly suitable for merchandizing women's sheer hose, although it can be used to equal advantage for the sale of any other kind of hosiery.

One of the objects of the invention is to provide a hosiery package which can be sealed at the mill and delivered to the ultimate consumer in such sealed condition and without the goods contained in such package being handled by others.

Another object of the invention is to provide a sealed hosiery package capable of displaying the hosiery contained therein so as to enable a customer to ascertain the quality and other characteristics of such hosiery.

A further object of the invention is to provide a hosiery package which is so constructed that the hosiery may be inserted into, and removed from the same, with relative ease and without damage.

A still further object of the invention is to provide an attractive hosiery package of such form that it is convenient to pack and handle, and capable during such handling, of maintaining the hosiery contained therein in an unwrinkled and undamaged condition.

Other objects of the invention as well as the features of novelty thereof, will become apparent after a perusal of the following description when read in connection with the accompanying drawings in which Figs. 1 to 6 inclusive, are perspective views illustrating the successive steps employed in forming the hosiery package shown in Figs. 7 to 9 of the drawings; Fig. 7 is a longitudinal sectional view of a hosiery package made in accordance with the invention; Fig. 8 is an end view showing the left-hand end of the package in Fig. 7; Fig. 9 is an end view showing the right-hand end of the package in Fig. 7 and Figs. 10 to 14, inclusive, illustrate the successive steps used in forming the hosiery package of this invention by another method.

Referring first to the embodiment of the invention illustrated in Figs. 1 through 9 of the drawings, the reference numeral 1 designates generally a pair of women's high grade sheer hosiery having the top ends 2 usual in such type of hosiery. In packaging such hosiery in accordance with the invention, one or more pairs thereof are first folded substantially midway of their lengths about the top edge 3 of a spring member 4, as is shown in Fig. 1 of the drawings. The member 4 is rectangularly-shaped and has a width approximately the same as the greatest width of the

2

hosier 1 and a length substantially equal to one-quarter of the length of such hosiery. For the purposes of the invention, the member 4 is constituted of a grade of "bond" paper having sufficient resiliency to tend to open up when rolled into cylindrical form, although any other suitable equivalent material may be used for the spring member 4.

After the hosiery 1 has been placed on the upper edge of the spring member 4 in the manner above noted, the lower or foot end of the hosiery is folded upwardly about the bottom edge 5 of the member 4 so that it is positioned between the ends 3 and 5 of such member, and intermediate such member, and the upper portion of the hosiery. Preferably also, the foot portion of the hosiery is folded along a longitudinal line in substantial alignment with the front edges of the flattened hosiery, so that such foot portion lies entirely within the area of the member 4. The upper end of the hosiery is then folded about the bottom edge 5 of the member 4 so that the upper end 2 of the hosiery overlies the calf portions thereof and is adjacent to the upper edge 3 of the member 4, as is shown in Fig. 2 of the drawing. This completes the mounting of the hosiery 1 on the spring member 4.

The member 4 with the hosiery 1 folded thereon, is then laid flat on a sheet of transparent, thermoplastic material 6, such as cellulose acetate, with the upper edge 3 of the member 4 spaced slightly beyond an end edge of the sheet 6 and the side edges of such member spaced equally from the side edges of the sheet. The sheet 6 has a length slightly greater than the length of the member 4 but is substantially wider than the latter. With the parts thus positioned, they are rolled together in the manner illustrated in Fig. 4 of the drawings, into a close roll 7. The ends of the rolled sheets 6 are then twisted about the longitudinal axis of the roll to form a tightly twisted teat 8 at each end of the roll (note Fig. 5). One of the teats 8 may be pressed into the end of the roll leaving the other teat projecting axially from the roll as is shown in Fig. 7 of the drawings.

The roll 7 is then inserted into a container 9 in the manner illustrated in Fig. 6 of the drawings. As is shown in Figs. 6 through 9 of the drawings, the container 9 includes a cylindrically-shaped body 10 having an overall length of approximately 6½ inches and an inside diameter of approximately 1½ inches, thus making it convenient for the manufacturer to pack a number of such packages in a carton and for the customer to carry in her bag. The body 10 of the

container is made of a .005 inch thick sheet of transparent thermoplastic material, such as cellulose acetate, which is overlapped and cemented or sealed along its longitudinal edges. The end portions 11 and 12 of the body 10 are printed to provide opaque end sections leaving the intermediate portion of the body clear and transparent. The ends of the body 10 are provided with inturned beads 13 and 14 whose edges abut against the interior surface of the body 10. Engaging the bead 13 is a bottom disc 15 having a diameter such, that it forms a tight fit in the body 10 and being constituted of relatively heavy paper, such as six ply chipboard. The container is closed by a top disc 16 which is tightly fitted in the body 10 adjacent to the top bead 14. The top disc 16 is made of substantially lighter material than the bottom disc 15 and preferably is constituted of two ply chipboard. As can be seen more clearly in Figs. 7 and 9 of the drawings, the top disc 16 is provided with a central opening 17 of relatively large size and through which the teat 8 on the adjacent end of the roll 7 may project.

It will be understood from the foregoing, that the package of this invention includes three elements which cooperate together to accomplish the results desired, namely, the hosiery mounting member 4, the wrapper 6 and the container 9. The member 4 by reason of its inherent resiliency functions as a spring to maintain the hosiery against the wrapper 6 and to maintain the latter against the body 10 of the container. As a result of this action of the member 4, the hosiery is maintained in a smooth condition and prevented from wrinkling in shipment and while being handled. Thus, the hosiery is always maintained in an attractive condition for display. Due also to this action of the member 4, the quality, pattern, design and other characteristics of the hosiery are divulged to better advantage through the transparent wrapper and container. Also because of the member 4, in cooperation with the end discs 15 and 16, the roll 7, comprising the hosiery, member 4 and wrapper 6, is prevented from shifting or moving within the container during shipment or handling, thus maintaining the appearance of the package unchanged from the time it leaves the mill until it reaches the ultimate consumer.

The wrapper 6 not only cooperates with the member 4 to prevent the hosiery from wrinkling in shipment, but functions in the nature of a lubricant to facilitate the insertion of the roll 7 into the container at the mill and its removal from the container by the ultimate consumer. The wrapper 6 also acts as a shield against damage to the hosiery by any sharp portions that may exist on the container because of faulty manufacture of the latter, or produced thereon by being improperly opened.

As has previously been mentioned, the construction of the container 9 is such that it cooperates with the member 4 to prevent shifting or movement of the roll 7 relative thereto; the dimensions of the container with relation to the roll 7 being so correlated that the latter maintains the end discs 15 and 16 seated against the inturned beads 13 and 14, respectively, during handling and shipment of the package. The body 10 of the container enhances the attractiveness of the package by reason of its opaque end portions 11 and 12 which conceal the irregular edges of the convoluted hosiery and member 4 and the wrinkled ends of the wrapper 6, and at the same time, affords sufficient display of the

hosier to give the customer a clear understanding of its construction and other characteristics. The form of the container 9 and the rigidified, smooth surface of its body portion 10 permit the package to be either attractively displayed on a counter or in a carton or to be delivered as by a slide, from a place of storage to the place of sale without damage to the hosiery.

As has been previously mentioned, the disc 16 is relatively light and can be readily removed by the customer either by inserting a fingernail under an edge of the opening 17 thereof, or by gripping the projecting teat 8 and pulling on the roll 7. Because of the roll form of the bead 14 and the lubricating action of the wrapper 6, the roll 7 may then be removed from the package with relative ease.

While a preferred form of the invention has been hereinabove described and illustrated in Figs. 1 through 9 of the drawings, it will be evident to those skilled in the art that modifications and changes in the package may be made without departing from the spirit of the invention. For example, instead of constructing the roll 7 in the manner illustrated in Figs. 1 through 5 of the drawings, such roll may be formed by folding the hosiery 1 around the member 4 in the manner shown in Figs. 1 and 2 of the drawings, and then folding such parts along the line 20-20 shown in Fig. 10 of the drawings to attain the folded condition of such parts shown in Fig. 11 of the drawings. The thus folded hosiery and member 4 are then placed in the center of a transparent wrapper 6' in the manner shown in Fig. 12 of the drawings. The wrapper 6' is then enclosed about the mounted hosiery by first folding two opposed corners of such wrapper over the mounted hosiery and then folding the two remaining corners over such mounted hosiery and finally securing the overlapping apexes of such corners in position by a seal 21 to produce the package 22 shown in Fig. 13 of the drawings. The package 22 is then formed into a tight roll 7' for insertion into the container 9 as shown in Fig. 14 of the drawings. After such insertion, a disc 16 is inserted in place to produce the package shown in Figs. 7 through 9 of the drawings.

I claim:

1. A hosiery package having a cylindrical form and comprising a cylindrical container including a tubular body portion of fixed diameter and composed at least in part, of transparent material and having turned in ends forming beads, a pair of end discs loosely positioned in said body portion and seated on said beads, at least one of said discs being removable from said body portion through its associated bead, a roll located in said body portion and having a length such as to maintain said discs seated on said beads, said roll including a mounting member, a pair of stockings folded on said member and a wrapper of smooth transparent material enclosing said member and stockings, said member, stockings and wrapper being rolled into the form of a roll in which such member, stockings and wrapper are arranged in spiraled relation and said mounting member being composed of a material having sufficient inherent resiliency to tend, in its rolled condition, to expand the rolled stockings and wrapper radially outwardly against said tubular body portion, the removable end disc of said container being provided with a central opening, and one end of said wrapper being twisted into the form of a teat and exposed by 75 said disc opening.

2. A cylindrically-shaped hosiery package composed of a pair of stocking and a wrapper of smooth, transparent material formed into a roll, and a cylindrically-shaped container for said roll, said container including a unitary sheet of relatively non-stretchable material having its longitudinal edges secured together to form a tubular body portion of fixed diameter, said body portion having a length such that its ends project slightly beyond the ends of the stocking roll enclosed thereby and having opaque end sections of substantial width to conceal the end portions of said stocking roll and being transparent intermediate said opaque end sections to expose to the view of an observer the intermediate portion of said stocking roll, the opaque end sections of said body portion being rolled inwardly to provide internal beads, a pair of end discs each contained within said body portion between said beads and each engaging the inner surface of a bead to close an end of said body portion, said stocking roll being formed to press resiliently radially outwardly to bring its outermost layer into smooth, snug engagement with the interior surface of said body portion and having a length such as to maintain

5

said end discs seated on said beads, one of said end discs being constituted of relatively light, readily distortable material and provided with a central opening to enable the fingernail of a user to be inserted therethrough and by an outwardly applied force to be readily withdrawn in distorted condition past the relatively rigid bead on which it is seated, said radially resilient stocking roll being compressible to permit its withdrawal past the inturned bead on which said light paper end disc is seated.
